[57] CLAIM

The ornamental design for a hair curler, as shown and described.

DESCRIPTION

FIG. 1 is a front elevational view of a hair curler showing my new design, the side opposite being a mirror image of the side shown;

FIG. 2 is a left side elevational view thereof, the side opposite being a mirror image of the side shown;

FIG. 3 is a top plan view thereof;

FIG. 4 is a bottom plan view thereof;

FIG. 5 is a front elevational view shown in a folded and partially expanded condition;

FIG. 6 is a front elevational view of a second modified embodiment, the side opposite being a mirror image of the side shown;

FIG. 7 is a left side elevational view thereof, the side opposite being a mirror image of the side shown;

FIG. 8 is a top plan view thereof;

FIG. 9 is a bottom plan view thereof;

FIG. 10 is a front elevational view of a third modified embodiment, the side opposite being a mirror image of the side shown;

FIG. 11 is a left side elevational view thereof, the side opposite being a mirror image of the side shown;

FIG. 12 is a top plan view thereof; and,

FIG. 13 is a bottom plan view thereof.
